UNITED STATES PATENT OFFICE.

ELLEN S. GETCHELL, OF BOSTON, MASSACHUSETTS, ASSIGNOR TO ANNA M. COUDREY, OF SAME PLACE.

BOOK-COVER.

SPECIFICATION forming part of Letters Patent No. 295,996, dated April 1, 1884.

Application filed July 9, 1883. (Model.)

To all whom it may concern:

Be it known that I, ELLEN S. GETCHELL, of Boston, in the county of Suffolk and State of Massachusetts, have invented new and useful 5 Improvements in Book-Covers, of which the following is a specification.

This is a cover for books, made of any material, but preferably of tough paper, and so constructed that it may be easily placed upon 10 and removed from a book for the protection of the binding, and that when applied to its purpose it will remain securely in place without slipping off. Provision is made also for recording the number of any page in the book.

15 In the accompanying drawings, in which similar letters of reference indicate like parts, Figure 1 represents my improved book-cover with one of the flaps laid back the better to illustrate the invention. Fig. 2 is a section 20 on line $x x$, Fig. 1.

A represents the body or main portion of the cover provided with the usual tongues a for lying in the spring-back of the book, and flaps b for folding over the front edges of the 25 binding.

B B are flaps provided with the hook-shaped portions or extensions B'. The hooks B' are narrow at their necks B'', and hook-shaped and bulbous at their ends B', as shown. To 30 secure the cover on the book, they are inserted through the slits c in the flaps b, where they remain securely on account of their shape.

In book-covers the strain comes heavily on the flaps B, such strain being from the point 35 where the inner edges of such flaps join the main portion of the cover A—*i. e.*, the point in the drawings between the flaps B and the tongues a to the slits c. The tendency is, of course, to pull out the flaps B, especially if the book binding be a thick one. To obviate this 40 difficulty, I make all the hooks to project inwardly, as shown—*i. e.*, toward the center of the cover—in order that they may resist the strain and not slip out.

45 In order that the reader may ascertain the number of the page reached at the last reading

of the book, strips D are provided, each bearing numbers from 1 to 9, inclusive. These strips are held in one of the flaps b by passing them through slits d in said flaps, and the figures may be seen through a slot, e, therein. Any desired number may be produced by proper longitudinal relative movement of the strips. The number of the strips may be varied at will. 50

This book-cover is especially useful for large 55 libraries, different sizes being provided for the well-known regular book sizes.

I am aware that in other articles—such as paper boxes, for instance—there have been 60 constructed hooks from the material of which such boxes are made, said hooks being for the purpose of holding the parts of the boxes together. I do not claim that hooks of this description are in themselves considered novel; 65 but I am not aware that they have been used in connection with book-covers, especially when arranged to project inwardly, as shown, thereby serving a purpose important to a book-cover. 70

Having thus fully described my invention, what I claim, and desire to secure by Letters Patent, is—

1. The herein-described improved book-cover, consisting, essentially, of the main portion A, side flaps, b, provided with the slits c, and hooked flaps B B' B'', the hooks B' on said flaps being all cut and arranged, as shown, to project inwardly toward the center of the book-cover, all constructed substantially as 75 and for the purpose set forth.

2. The combination, in a book-cover, of the main portion A, provided with the side flap, b, said side flap having the slits d and slot e, and the numbered strips D, constructed and 85 arranged substantially as and for the purpose described.

ELLEN S. GETCHELL.
